UNITED STATES PATENT OFFICE.

GEORGE R. WEBBER, OF AUGUSTA, MAINE.

DESIGN FOR A COMBINATION VENDING AND DISPENSING CASE.

Application filed January 3, 1928. Serial No. 24,742. Term of patent 14 years.

To all whom it may concern:

Be it known that I, GEORGE R. WEBBER, a citizen of the United States, residing at Augusta, county of Kennebec, State of Maine, have invented a new, original, and ornamental Design for a Combination Vending and Dispensing Case, of which the following is a specification, reference being had to the accompanying drawing, forming part thereof.

Fig. 1 is an elevation showing my new design for combination vending and dispensing case.

Fig. 2 is a top plan view of the same.

I claim:

The ornamental design for a combination vending and dispensing case, as shown.

GEORGE R. WEBBER.
